UNITED STATES PATENT OFFICE.

WILLIAM J. QUINN, OF BALTIMORE, MARYLAND, ASSIGNOR TO THE HENRY MC SHANE MANUFACTURING COMPANY, OF SAME PLACE.

GLOBE-VALVE.

SPECIFICATION forming part of Letters Patent No. 485,055, dated October 25, 1892.

Application filed June 2, 1892. Serial No. 435,286. (No model.)

To all whom it may concern:

Be it known that I, WILLIAM J. QUINN, a citizen of the United States, residing at Baltimore, in the State of Maryland, have invented 5 certain new and useful Improvements in Globe-Valves; and I do hereby declare the following to be a full, clear, and exact description of the invention, such as will enable others skilled in the art to which it appertains to make and use the same.

This invention has relation to globe-valves such as are especially designed and adapted for use on steam pipes and fittings, and has for its object the provision of novel means for 15 rendering the valve perfectly steam-tight when turned down upon its closing-seat and for preventing leakage when the valve is raised and caused to seat against the under side of the box, as may be sometime required 20 when it is necessary to renew the packing in the upper part of the box.

This invention has for its further object the provision of a novel construction and arrangement of the valve proper and of the collar and nut by which it is secured upon the spindle, whereby the valve is rendered reversible, the packing-disk made interchangeable and reversible, and the valve prevented 25 from turning and grinding or wearing after 30 being seated.

My invention consists in the novel construction, combination, and arrangement of parts as hereinafter described and specifically claimed.

35 In the accompanying drawings, Figure 1 is a vertical central sectional view of a globe-valve embodying my invention. Fig. 2 is a horizontal sectional view of the same on the line X X of Fig. 1.

40 The valve-casing A is of the usual construction, and is provided with the box B, through which passes the spindle D, carrying on its lower end the valve E. Above the internally-screw-threaded part of the box B the ordinary 45 cavity b is formed for the reception of packing material. A screw-threaded cap e surrounds the box B and is formed with a central opening for the passage of the smooth cylindrical portion of the valve-stem. On the 50 under side of the box B is formed an annular valve-seat F, against which the upper side of

the valve is pressed and the valve seated when the latter is raised to its highest point of adjustment.

The valve E for the purposes of my invention consists of a cylindrical block or head, having a central opening for the passage of the spindle D, and having in its upper and lower faces cylindrical cavities or recesses for the reception of the vulcanized packing-disks 55 G G', which fit snugly in place and have central openings corresponding to the central openings in the web of the valve-head. When the valve-head is in place upon the spindle, the upper surface of the disk G rests against 60 a collar h, formed upon the spindle D, and the valve is held in position by means of a flanged cap-nut I, which screws upon a threaded tenon on the lower end of the valve-spindle, a shoulder k being left on the spindle 65 to prevent the nut from being screwed up tightly enough to bind the valve-head or prevent easy rotation. It is important and very desirable that the valve-head should have a certain amount of play upon the spindle and 70 that it should be able to freely rotate upon the same, so that when the valve is seated upon its annular seat C the valve-stem may be turned independently of the head and the valve tightly compressed against its seat without 75 turning or grinding upon the same. When the valve is raised as high as possible, its upper surface seats against the annular flange 80 F and produces a perfectly-steam-tight joint, which permits of the cap e being removed and 85 the spindle-box packed without danger of leakage.

It will be seen that the packing-disks G G' and the recesses in the valve in which said packing-disks fit are exactly alike in shape 90 and dimensions, and that under these conditions the valve-head may be reversed on the spindle, either disk inverted, or the disks interchanged, so that the wear upon the disks may be readily compensated for and their 95 serviceableness greatly prolonged.

The valve E, as already indicated, is loose upon the stem D. Hence when the valve is lowered upon its seat C the upper disk G is compressed tightly against the collar h, thus 100 producing a tight joint around the collar and preventing leakage at that point, and when

the valve is raised and seated against the annular flange F the lower disk G' is pressed tightly against the flanged cap-nut I, thus producing a tight joint at the contacting-surfaces and preventing the passage of steam from below the valve up into the box.

Having described my invention, I claim—

In a globe-valve, the combination, with the spindle, of a valve through which said spindle passes and upon which the valve may be rotated, said valve consisting of a cylindrical

block or head having like recesses in its upper and lower faces containing reversible and interchangeable packing-disks, substantially as described.

In testimony whereof I affix my signature in presence of two witnesses.

WILLIAM J. QUINN.
